United States Patent Office

Des. 197,147
Patented Dec. 17, 1963

197,147

DISPLAY CARTON OR SIMILAR ARTICLE

Ernest L. Shapiro, Morton Grove, Ill., assignor to Alberto-Culver Company, Melrose Park, Ill., a corporation of Delaware

Filed May 22, 1963, Ser. No. 75,014

Term of patent 14 years

(Cl. D58—12)

I claim:

The ornamental design for a display carton or similar article, as shown.
